UNITED STATES PATENT OFFICE

115,048

DESIGN FOR A STOVE

John R. Morgan, Oak Park, Ill., assignor to Sears, Roebuck and Co., Chicago, Ill., a corporation
of New York

Application September 10, 1938, Serial No. 79,837

Term of patent 7 years

To all whom it may concern:

Be it known that I, John R. Morgan, a citizen of the Republic of Guatemala, residing at Oak Park, in the county of Cook and State of Illinois, have invented a new, original, and ornamental Design for a Stove, of which the following is a specification, reference being had to the accompanying drawing, forming a part thereof.

Fig. 1 is a plan view of a stove embodying my new design.

Fig. 2 is a front elevation thereof.

Fig. 3 is a side elevation thereof.

I claim:

The ornamental design for a stove, substantially as shown.

JOHN R. MORGAN.
